UNITED STATES PATENT OFFICE.

GEORGE R. STINE, OF SAN FRANCISCO, CALIFORNIA, ASSIGNOR OF ONE-HALF TO
CHARLES W. SPRINGSTEEN, OF SAN FRANCISCO, CALIFORNIA.

FOLDING COT.

1,257,041.

Specification of Letters Patent. Patented Feb. 19, 1918.

Application filed October 23, 1916. Serial No. 127,043.

To all whom it may concern:

Be it known that I, GEORGE R. STINE, a citizen of the United States, residing at the city and county of San Francisco and State of California, have invented new and useful Improvements in Folding Cots, of which the following is a specification.

This invention relates to a folding cot.

One of the objects of the present invention is to provide a simple substantial, cheaply manufactured folding cot and particularly a structure which may be used as a cot, a stretcher, or as a hammock.

Another object of the invention is to provide a structure of the character described which can be quickly and readily extended for use and which can be folded into such a compact bundle that it can be readily handled and carried around on a pack when in the field, or camping, and which will consume a comparatively small space when stored away for future use. Another object of the invention is to provide a novel pillow supporter, and also a novel stretcher by which the center portion of the canvas may be supported independent of the end sections of the cot.

Further objects will hereinafter appear.

The invention consists of the parts and the construction and combination of parts as hereinafter more fully described and claimed, having reference to the accompanying drawing, in which:—

Figure 1 is a side elevation of a cot.

Fig. 2 is a plan view of same partly broken away, showing the supporting legs in position to be connected.

Fig. 3 is a fragmentary view of one end of Fig. 4, showing the parts in folded position.

Fig. 4 is a perspective view of the stretcher frame.

Fig. 5 is a perspective view of the cot showing it in use as a stretcher.

Fig. 6 is a partial plan view of one end of the cot showing the pillow support.

Fig. 7 is a perspective view of one of the stretcher legs showing the handle extension formed thereon.

Fig. 8 is a perspective view of the cot when used as a hammock.

Fig. 9 is an end view in section showing the position of the bracing legs.

Fig. 10 is a perspective view of the lower

end of one of the bracing legs and one of the main supporting legs.

Fig. 11 is a perspective view showing a form of hook employed on the stretcher frame.

Fig. 12 is a perspective view showing the form of hook used in connection with the stretcher only.

Fig. 13 is an enlarged side elevation of the pillow support, partly in section.

Referring to the drawings in detail, A indicates a canvas or mattress portion of the cot which in this instance is secured to a pair of end sections 2 and 3. Hingedly connected to the end section 2 as at 4 and 5 is a pair of supporting legs 6 and 7, each of which consists of two sections 6 and 6^a and 7 and 7^a, which in turn are hingedly connected at 8 and 9. Similarly secured to the opposite end section 3 as at 10 and 11, is a pair of supporting legs 12 and 13 which also consists of two sections which are hingedly connected as at 14 and 15. The legs 6 and 12 when folded together about their respective hinges 8 and 14, are adapted to be swung about their main connecting hinges 5 and 10 to lie outside of the main end sections 2 and 3 as shown in Fig. 2 when the cot is folded, while the legs 7 and 13 when folded about their hinges 9 and 15 are adapted to lie parallel with and inside of the main end sections 2 and 3. The leg sections when folded outwardly about their respective hinges to lie parallel with each other and crossed as shown in Fig. 1 are secured together by screws 16 which pass through each pair of legs and into the main cross bar 17 of the stretcher frame generally shown in Fig. 4. The screws 16 when the main supporting legs are extended to support the top as shown in Fig. 1, not only form a means whereby each pair of legs are secured together, but they also provide supports for the cross-bar 17 which is tapped at each end indicated at 18 to receive said screws. The stretcher frame proper consisting of the cross bar 17 is provided with two upwardly extending arms 19 which are pivotally secured thereto as at 20, and each arm 19 is in turn provided with a pivotally mounted cross-arm 21 on which are fastened hooks 22 provided for the purpose of engaging eyelets 23 placed in the sides of the canvas A, in this manner providing a

central support for same, which may be adjusted to permit stretching or contracting of the canvas as desired. A pair of latching arms 24 pivotally secured to the cross bar 17, and engageable with pins on the uprights 19 permits each cross arm 21 to be adjusted to give the canvas any stretch desired.

While any suitable form of hook may be employed, I wish it understood that the form as shown in Fig. 11 is preferable.

Adapted to be inserted in one end of each leg 6 and 7 is an angularly bent rearwardly extending arm 24^a. The inner end 15 of each arm is preferably square in cross section where it is inserted through the main supporting legs 6 and 7, this construction being provided for the purpose of preventing any turning movement. The arms 20 24 extending rearwardly, are provided as holders and receivers for a canvas 25. This canvas slipped over the outer ends of the arms 24, forms a pillow, or pillow support, and as the inner end of the canvas is extended to form a flap 26, it can readily be seen that a continuous covering between the pillow support and the canvas bottom A is provided which prevents draft or cold from disturbing anyone using the cot. This pillow extension is a great convenience as it not only raises the head into comfortable position, but also permits people of considerable height to sleep with comfort on an ordinary cot.

35 This pillow support or extension as previously described consisting of the canvas 25 and the insertible rearwardly extending arms 24, may be removed when the cot is to be folded, by merely pulling each arm 40 out of its socket. They may then be placed together and the canvas 25 wrapped around the same, and they are then placed within the cot and the main canvas A when the parts are rolled together, or, as shown in 45 Fig. 3, it becomes possible to place said extension arms together with the canvas on top of the stretcher frame shown in Fig. 3.

The stretcher frame shown in Fig. 4 is also adapted to be folded into a compact 50 bundle, as the uprights 19 are pivotally secured to the cross bar 17, and the cross arms 21 are in turn pivotally secured to the uprights. They may therefore be folded together as shown in Fig. 3 and therefore 55 consume comparatively small space when wrapped together with the main parts of the cot. In folding the frame shown in Fig. 4, cross arms 21 are swung about their pivots to lie parallel to or aline with uprights 19, whereupon the latter are swung inwardly about their pivots 20 to be disposed between the ends of cross bar 17, as 60 shown in Fig. 3.

When it is desired to use the cot for ordinary sleeping purposes, it is erected as

shown in Fig. 1. While the end sections 2 and 3 and the stretcher frame shown in Fig. 4 steadies the cot against lateral and longitudinal movements, it is possible to further reinforce and strengthen the structure as a whole by a pair of laterally disposed bracing legs 27 secured to each end section 2 and 3. These legs are more clearly shown in Figs. 9 and 10 and are constructed and mounted as follows:

75 Formed in each end section 2 and 3 is a cut-away portion 28 in which is secured a metal plate 29. Hingedly secured to each end of this plate as at 30 is a bracing leg 27. One leg is pivotally secured on one 80 side of the plate, while the opposite leg is pivotally secured on the other side of the plate. This construction permits the legs to be folded down within the cut-away portion on opposite sides of the plate 29, and 85 therefore requires comparatively small space. The lower end of each leg 27 is enlarged and slotted as at 32 to permit it to engage a headed bolt 33 secured near the outer end of the supporting leg.

90 Extending or unfolding of the cot for use, is first accomplished by unrolling the main canvas A to permit the main supporting legs to be unfolded and secured together as shown in Fig. 1. The lateral bracing 95 legs 27 are then swung down from the end sections and sprung over the headed bolts 33. The cot is in this manner rigidly braced both against lateral and longitudinal movement, as all strains are taken care of 100 by the construction and position of the leg structure shown. The hinges 8 and 9 together with the hinges 14 and 15 are so positioned with relation to each other that they become offset as indicated at 30, see 105 Fig. 1. This is of considerable importance as it not only permits the insertion of the screw 16 but also increases the rigidity of the main supporting legs to a considerable extent. If the cot is to be employed as a 110 stretcher it is only necessary to swing the main supporting legs up in under the main canvas A as shown in Fig. 5. The screws 16 are in this instance not employed but are however substituted by screws 31 which 115 pass through each pair of legs; these screws securing the legs rigidly together.

The structure frame indicated in Fig. 4 is also eliminated and as the main supporting legs are folded up in under the canvas 120 bottom, it becomes necessary to provide auxiliary supporting legs such as shown at 32^a. These legs may be constructed in any suitable manner either by casting or drop forging, and are preferably provided with a 125 flange 33^a on the upper end, sufficiently long to embrace the main supporting legs, and a similar inwardly projecting flange 34 to embrace the lower side of the supporting legs. The flanges 33 and 34 being offset 130

with relation to each other as shown, forms a rigid grip and brace which cannot readily be removed or displaced when in use.

Each leg is further secured by means of 5 a screw 38, and as each leg is provided with a handle extension 39, it can readily be seen that the cot or stretcher may be easily lifted and carried about.

A cot structure thus provided, may not 10 only be used for hospital use and like service, but has proven of incalculable value so far as field and general work service is concerned.

Another form of structure is shown in 15 Fig. 8. The cot as here employed is used as a hammock and this result is brought about by merely folding up the main supporting legs as shown. The legs are then tied together by a rope 40 at each end, which 20 is extended to permit it to be tied or hung on posts or other similar supports such as shown.

The stretcher frame shown in Fig. 4 together with the pillow support used in connection with the cot structure shown in 25 Fig. 1, may in this instance be entirely eliminated, as may also the brace legs 27.

A cot structure capable of as many uses 30 as here illustrated, has proven of great value, as it may not only be used as an ordinary cot when in field service or camping, but it may equally readily be employed as a hammock as illustrated in Fig. 8. Again it can readily be seen that it may easily be 35 converted into a structure which can comfortably be handled and quickly folded into a compact bundle when it is so desired.

In actual practice it is found that the cot 40 only measures five by six inches in circumference and three feet in length. As comparatively few parts are used and the structure as a whole is substantially and rigidly braced when employed, it can readily be seen that its general use and employment 45 is practically universal.

The several hinges employed throughout 50 the structure are all alike, and as but few screws are employed it is obvious that temporary disabling or the loss of parts is practically eliminated.

The materials and finish of the several parts of the cot may otherwise be such as the experience and judgment of the manufacturer may dictate.

55 I wish it understood that various changes in form, proportions and minor details of construction may be resorted to within the scope of the appended claims, and that I do not wish to limit myself to the specific design or construction here shown.

Having thus described my invention, what I claim and desire to secure by Letters Patent is:—

65 1. A cot comprising a canvas bottom, a pair of end sections to which said canvas is

secured, a pair of legs hingedly secured to each end section adapted to be swung about the hinges to extend at right angles to and coöperate with the end sections to form a rectangular stretcher frame for the canvas 70 bottom, means for securing the legs together when swung around to form a stretcher frame, auxiliary legs adapted to be secured to the stretcher frame sections, and a handle extension on each leg. 75

2. An auxiliary leg for a cot of the character described comprising an angle iron leg having an integral handle extension formed thereon, a projecting flange on the handle adapted to engage the lower side of the cot 80 frame, a flange extension on the upper end of the leg adapted to engage the upper side of the cot frame, and a screw extending through the leg adapted to enter the wood of the frame. 85

3. A cot comprising a canvas bottom, a pair of end sections to which said canvas is secured, a pair of sectional legs hingedly secured to each end section adapted to be swung out to extend at right angles to the 90 end sections to form a rectangular frame for a stretcher, the sections of the legs being movably connected so as to enable same to be folded parallel with the end sections to permit the canvas bottom to be used as a 95 hammock.

4. In a folding cot, end sections, a canvas bottom connected to said sections, a pair of sectional legs, means to movably connect the legs to the end sections to allow the same to 100 fold parallel to the end sections, means to movably connect the leg sections to each other to allow the latter to fold transversely of the cot to lie parallel to each other and to be extended to lie at right angles to the 105 end sections, and means to secure the legs of opposing end sections together in crossed extended relation so as to hold the bottom in operative position.

5. In a folding cot, end sections, supporting means therefor, a canvas bottom connected to the end sections, a cross bar connected to said supporting means and arranged at approximately the longitudinal center of the canvas bottom, foldable uprights connected at their lower ends to the cross-bar, and foldable cross arms connected to the upper ends of the uprights and extending longitudinally of and connected to the canvas bottom. 110 115

6. In a folding cot, end sections, supporting means therefor, a canvas bottom connected to the end sections, a cross bar connected to said supporting means and arranged at approximately the longitudinal 120 center of the canvas bottom, foldable uprights pivotally connected to the cross bar, means to hold the uprights against inward pivotal movement, and cross arms pivoted at their longitudinal centers to the uprights 125 130

and extending longitudinally of and connected to the canvas bottom, said cross bars and uprights being so pivoted and related that the cross bars may be moved to lie parallel to the uprights and with the latter swung to lie between the ends of the cross bar.

7. In a folding cot, end sections, a pair of hingedly connected legs for each end of each 10 end section, one of which legs of each pair is hinged to the respective end of the end section to allow the legs of each end section to be folded to lie parallel to the latter to thereby permit the end sections to be suspended to form a hammock or folded for 15

transportation or storage, means to connect the legs in crossed relation when extended and arranged at right angles to the end sections, means to hold the legs when extended in rigid parallel relation to allow the device 20 to be used as a stretcher, and a canvas bottom engaged with the end sections.

In testimony whereof I have hereunto set my hand in the presence of two subscribing witnesses.

GEORGE R. STINE.
